DESIGN FOR A CONNECTING LINK FOR CHAINS

Fredrick Paul Miller, Vulcan, Mich.

Application July 25, 1935, Serial No. 57,805

Term of patent 7 years

To all whom it may concern:

Be it known that I, Fredrick Paul Miller, a citizen of the United States, residing at Vulcan, in the county of Dickinson and State of Michigan, have invented a new, original, and ornamental Design for a Connecting Link for Chains, of which the following is a specification, reference being had to the accompanying drawing, forming part thereof.

Figure 1 is a view in side elevation of a connecting link for chains showing my new design.

Figure 2 is an end view of the link.

Figure 3 is a front elevational view.

I claim:—

The ornamental design for a connecting link for chains, as shown.

FREDRICK PAUL MILLER.
